UNITED STATES PATENT OFFICE

DOMENIC M. CAMPANA, OF WILMETTE, ILLINOIS

CLOTHES HANGER

Application filed November 9, 1927. Serial No. 232,013.

This invention relates to a combined hat and coat hanger and has for one of its objects the provision of a device which will support a hat and coat in a position to simulate the form of a person.

A further object of the invention is to provide a hat and coat rack which shall be simple and economical to manufacture and which will attract attention.

10 A still further object is to provide a device of the class named which shall be of improved construction and operation.

The invention is exemplified in the combination and arrangement of parts shown 15 in the accompanying drawing and described in the following specification, and it is more particularly pointed out in the appended claims.

In the drawing—

20 Fig. 1 is a front elevation of one embodiment of the present invention having a hat and coat carried thereby;

Fig. 2 is a side elevation of the device shown in Fig. 1;

25 Fig. 3 is a vertical section showing the manner of attaching two parts of the device together; and

Fig. 4 is a section on line 4—4 of Fig. 2.

The numeral 10 designates a supporting 30 plate which may be of any suitable shape, an oval form being illustrated in the drawing. The plate is provided at its upper edge with an eye 11 by means of which the device may be hung upon a hook or other 35 suitable support 12. A bracket 13 is secured to the plate 10 and projects forwardly therefrom. The plate 10 may have an opening 14 therethrough and the bracket 13 is provided with a tongue 15 which extends

40 into the opening 14 and fits tightly therein. The opening 14 is preferably rectangular in shape to prevent the bracket 13 from rotating. A nail or other fastening device 16 may be driven through a portion of the plate 10 and the tongue 15 to hold the plate and bracket together. At its forward end the bracket 13 is recessed, as shown at 17, and a hook 18 is positioned within the recess. A hat support 19 is carried at the forward end of the bracket 13 and preferably

comprises an upright portion 20 having the front face thereof carved or otherwise decorated to simulate a person's face. The member may be made of wood and carved and painted, or it may be made of wood and have a face drawn or painted on the front surface thereof, or it may be made of papier-mâché, wax or other suitable material and have the front surface thereof shaped and decorated to simulate the face of a person.

The upright portion 20 is provided with a screw-eye 21 which engages the hook 18 and holds the upright portion in place on the bracket 13. The upright portion 20 may be provided with a backwardly extending rounded portion 22 for supporting a hat 23 in the manner in which a hat is worn upon a person's head. The portion 22 may be omitted and the hat placed upon the plate 20 with the rear portion resting upon the bracket 13. A screw-eye 24 or other support is attached to the lower face of the bracket 13 and a coat hanger 25 is suspended from the screw-eye. The hanger 25 is preferably located at such a height that when it supports a coat 26 the coat will assume substantially the position of the body of a person having the face represented on the plate 20. It will be seen from Fig. 1 that when the clothes hanger is provided with a hat and coat the assemblage simulates the upper portion of a person's body. The face on the part 20 may be decorated to appear grotesque or humorous so as to attract attention.

The device may be used for displaying goods, or may be used as a novelty in public places, such as restaurants, and many other places of use will readily suggest themselves to persons interested in the art.

I claim:—

1. A clothes hanger comprising a horizontally extending bracket, a hat supporting member simulating the head of a person carried at the forward end of said bracket and extending upwardly therefrom, and a coat hanger suspended below said bracket.

2. A clothes hanger comprising a horizontally extending bracket, an upright member simulating the head of a person mount-

ed at the forward end of said bracket for supporting a hat on the upper portion thereof, and a coat hanger disposed below said bracket at a height approximately level with the lower portion of said upright member.

3. A clothes hanger comprising a plate, means for attaching said plate to a support, a bracket secured to said plate and extending forwardly therefrom, an upright member mounted at the forward end of said bracket and having the front face thereof decorated to simulate the face of a person, and a coat hanger suspended from said bracket for supporting a coat in position to simulate the body of the person.

4. A clothes support comprising a horizontally extending bracket having a recess in the forward end thereof, a hook disposed in said recess, and a hat supporting member having an eye attached thereto for engaging said hook to connect said hat supporting member with said bracket.

5. A clothes support comprising a plate, means for suspending said plate, a horizontally extending bracket mounted on said plate, a hat support shaped and decorated to simulate the head of a person, a hook and eye connection for securing said hat support to the forward end of said bracket, an eye attached to the lower side of said bracket, and a coat hanger suspended from said eye.

6. A clothes hanger comprising a member simulating the head of a person formed to support a hat in normal wearing relation thereon, a bracket for supporting said member when said hat is properly disposed on said member to simulate the hatted head of a person, and a coat hanger disposed below said member for supporting a coat in position to simulate the body of a person.

7. A clothes hanger comprising a horizontally extending bracket, an upright member simulating the head of a person mounted at the forward end of said bracket for supporting a hat on the upper portion thereof, and a coat hanger carried by and disposed below said bracket at a height approximately level with the lower portion of said upright member.

In testimony whereof I have signed my name to this specification on this 2nd day of November, A. D. 1927.

DOMENIC M. CAMPANA.
